US00D675621S

(12) **United States Design Patent**
Fletcher et al.

(10) **Patent No.:** **US D675,621 S**
(45) **Date of Patent:** **** Feb. 5, 2013**

(54) **INTERACTIVE INPUT SYSTEM
COMPONENT**

(75) Inventors: **Mark Andrew Fletcher**, Nepean (CA);
Alan Peter Boykiw, Calgary (CA);
Cheng Guo, Calgary (CA); **Paul
Anthony Auger**, Osgoode (CA)

(73) Assignee: **SMART Technologies ULC** (CA)

(**) Term: **14 Years**

(21) Appl. No.: **29/408,920**

(22) Filed: **Dec. 19, 2011**

Related U.S. Application Data

(62) Division of application No. 29/363,312, filed on Jun. 8, 2010.

(51) **LOC (9) Cl.** **14-02**

(52) **U.S. Cl.** **D14/411**

(57) **CLAIM**

The ornamental design for an interactive input system component, as shown and described.

DESCRIPTION

FIG. 1 is a rear perspective view of one embodiment of the interactive input system component in accordance with our design;

FIG. 2 is a side view of the interactive input system component of FIG. 1;

FIG. 3 is a front view of the interactive input system component of FIG. 1; and,

FIG. 4 is a rear view of the interactive input system component of FIG. 1.
